INTERNAL COMBUSTION ENGINE.
APPLICATION FILED JAN. 23, 1917.

Patented Nov. 13, 1917.

2 SHEETS—SHEET 2.

UNITED STATES PATENT OFFICE.

ROY W. IDE, OF SPRINGFIELD, ILLINOIS, ASSIGNOR TO IDE PATENTS CORPORATION, OF SPRINGFIELD, ILLINOIS, A CORPORATION OF ILLINOIS.

INTERNAL-COMBUSTION ENGINE.

1,246,745.

Specification of Letters Patent.

Patented Nov. 13, 1917.

Application filed January 23, 1917. Serial No. 143,974.

To all whom it may concern:

Be it known that I, Roy W. Ide, citizen of the United States, residing at Springfield, in the county of Sangamon and State of Illinois, have invented a certain new and useful Improvement in Internal-Combustion Engines, of which the following is a full, clear, concise, and exact description.

My invention relates to internal combustion engines and is an improvement upon an engine which employs a rotating valving cylinder within an engine cylinder and a piston operating in the valving cylinder, the valving cylinder being provided with a closed head that receives the force of the explosions that occur between this head and the piston, the engine cylinder also having a closed head adjacent the closed head of the valving cylinder.

It is the main object of my invention to provide facility for lubricating the outer or upper engaging surfaces of the valving cylinder and engine cylinder and at the same time increase the efficiency in engines of this type. In carrying my object into effect I provide freedom for the flow of lubricant between the aforesaid heads of the engine cylinder and valving cylinder whereby lubricant may flow from this space and preferably also to this space to lubricate the engaging adjacent surfaces of the engine cylinder and valving cylinder. To afford this freedom of flow for the lubricant I provide a vent passage from the space intervening between the aforesaid cylinder heads. I find that the provision of this vent materially increases the efficiency of the engine as compared with the efficiency of a similar engine but lacking the vent. This vent desirably communicates with the crank pit or crank case, particularly where the lubricant is supplied from the crank case to the space between said cylinder heads, it being preferred to convey the lubricant to the

space between the cylinder heads by way of the intake port of the engine cylinder. As I have practised my invention the lubricant is carried in the form of vapor from the interior of the crank case by way of a passage that communicates with the said intake port, the lubricating oil being put in the form of vapor and carried by the flowing air to the intake port by mechanism of the engine which is within the crank case.

I will explain my invention more fully by

reference to the accompanying drawings showing the preferred embodiment thereof and in which Figure 1 is a sectional elevation on line 1—1 of Fig. 2 but with the piston and valving cylinder in different positions; Fig. 2 is a view on line 2—2 of Fig. 1; and Fig. 3 is a sectional plan view on line 3—3 of Fig. 2, Figs. 1 and 2 being somewhat irregular to have them respectively include the intake port and the spark plug.

Like parts are indicated by similar characters of reference throughout the different figures.

The engine illustrated is a single cylinder engine. The crank shaft 1 has its crank 2 in connection with one end of a pitman 3, the other end of the pitman being pivotally connected at 4 with the piston 5. A valve cylinder 6 is rotated in some suitable way as by means of a pinion 7 operated at suitable speed by some engine driven portion, this pinion engaging a spur gear 8 upon the lower end of the cylinder 6. The valving cylinder may be provided with ports 9 to control the admission of carbureted air or other gas through the intake port 10 in the cylinder 11 in which the valving cylinder rotates and also to control the passage of gas through the exhaust port 12 in the cylinder 11. The cylinder 11 is desirably provided with a jacket 13 for the reception of cooling fluid. This jacket is carried upon the upper end of the crank case 14 that contains lubricating oil 15 and which has an annular step 16 at its upper end upon which the lower end of the valving cylinder turns. An oil pump is shown which includes two meshing pinions 17, 18 that operate to withdraw oil from the oil pit and force it upwardly through the passages 19 that lead to the various bearing surfaces that are to be lubricated. Oil leaves certain of these bearing surfaces above the level of the lubricating oil 15 as indicated at 20, and the operating parts of the engine within the crank case serves to fan the oil as it leaves these bearings to produce a mist. Air is admitted to the crank case through the "breather" 21 or other intake openings or passages and a part of it is discharged from the crank case through the passage 22. This passage, in the form of the invention illustrated, communicates with the carbureting or mixing chamber 23 to which gasoline or other fuel is led from the nozzle 24 of a suitable form

of carbureter. The air rising through the passage 22 carries the subdivided particles of lubricating oil in the form of a mist and this oil charged air passes into the mixing chamber where it is carbureted, the flow of the carbureted air being regulated by some suitable form of throttle valve 25 as will be readily understood by those skilled in the art. The mixing chamber 23 communicates 5 with the intake port 10 of the engine cylinder 11. Carbureted air finds entrance to the valving cylinder through a port 9 when it communicates with the port 10. A portion of the lubricant carried by the carbureted 10 air finds passage into the space between the heads of the engine and valving cylinders and in passing to this space lubricates the adjacent engaging surfaces of these cylinders. Hitherto this lubricant has been 15 trapped in the space between the heads of the engine and valving cylinders and became baked leaving a solidified deposit which choked the space between these cylinder heads and retarded the flow of the lubricant 20 to such space, whereby the proper lubrication of the adjacent portions of the engine and valving cylinders was interfered with. I prevent the trapping of lubricant in this space by promoting the flow of lubricant 25 therethrough, a result which is accomplished by providing a vent passage 26 that communicates with such space and which affords the free flow of lubricant therefrom.

In the preferred embodiment of the invention this passage communicates with the crank pit so that the lubricant which is passed from the space between the cylinder heads is returned to the crank case. The manner in which the lubricant finds access 30 to the space between the cylinder heads will be understood by those skilled in the art, it being known that some of the oil will be deposited upon the rotating valving cylinder in the zone of its ports and will work its 35 way upward through the slight clearance that must intervene between the valving and engine cylinders. It is also known that the upward flow of the lubricant is due in part to the pressure to which it is subject during 40 the compression and expansion strokes of 45 the engine piston.

The other novel features of construction shown are set forth in my copending applications Serial Numbers 149,571, and 149,572,

both filed February 19, 1917. The first of 55 these two co-pending cases relates to the carbureter, while the other case is based upon features of construction that are inclusive of the "breather" 21, the passage 22; the valve mechanism and engine controlled means for 60 controlling the flow of fuel; and the provision of a sleeve for maintaining separation between chambers that contain lubricant and fuel.

While I have herein shown and particularly described the preferred embodiment of my invention I do not wish to be limited to the precise details of construction shown as changes may readily be made without departing from the spirit of my invention, but 70 having thus described my invention I claim as new and desire to secure by Letters Patent the following:

1. An internal combustion engine including an engine cylinder; a rotating valving cylinder provided with a closed head receiving the force of the explosions and located within the engine cylinder which has a head adjacent the head of the valving cylinder, there being space intervening between said cylinder heads; a piston within the valving cylinder; a shaft; a crank connected with the piston and shaft; and a lubricant containing crank case, passage intervening between the lubricant containing portion of 85 the crank case and the engaging portions of 90 said cylinders that are adjacent their heads for conveying lubricant to such portions and to the space between said heads, there being a vent communicating with the space between said cylinder heads.

2. An internal combustion engine including an engine cylinder; a rotating valving cylinder provided with a closed head receiving the force of the explosions and located 95 within the engine cylinder which has a head adjacent the head of the valving cylinder, there being space intervening between said cylinder heads; and a source of lubricant in communication with the space that intervenes between the cylinder heads and from which lubricant flows to such space, there being a vent communicating with the space 100 between said cylinder heads.

In witness whereof, I hereunto subscribe 105 my name this 30th day of December, A. D. 1916.

ROY W. IDE
